NEEDLE PROTECTOR FOR KNITTING MACHINES

Albert E. Page, Brooklyn, N. Y., assignor to Scott & Williams, Incorporated, New York, N. Y., a corporation of Massachusetts

Application August 2, 1935, Serial No. 34,458

14 Claims. (Cl. 66—157)

This invention relates to needle protectors for knitting machines and more particularly for knitting machines arranged for knitting plated rib and plain fabrics and having selected cylinder needles moved to plate the threads in the reverse relation during plain knitting and it is an object of this invention to provide in a knitting machine of the type described a needle protector for detecting "load-ups" and broken needles and particularly broken or defective needles which are moved backwards as the reverse plating needles are during plain knitting. It is also an object of this invention to provide a needle protector arranged to be operated to stop the machine in case of "load-ups", broken or defective needles or in case the spring band on the sinkers or web holders breaks, or if for any other reason the sinkers or web holders are positioned outwardly beyond their normal working position.

20 In the drawings in which the invention is shown embodied in a Scott & Williams rib knitting machine arranged for reverse plating in a well known manner,

Fig. 1 is a partial vertical section through a rib knitting machine of the type described showing a needle protector applied thereto and positioned as for detecting broken or defective needles during plain knitting;

Fig. 2 is a partial top plan view of the structure shown in Fig. 1;

Fig. 3 is a partial vertical section taken as on line 3—3 of Fig. 2;

Fig. 4 is a sectional view taken as on line 4—4 of Fig. 1 and showing in plan view the operating means for the needle protector;

Fig. 5 is a broken view, showing in front elevation the supporting means for the needle protector;

Fig. 6 is a plan view, similar to Fig. 3, but showing the needle protector in the position it occupies during rib knitting;

Fig. 7 is a fragmentary vertical sectional view showing the relative positions of the needle protector and a broken or defective needle which has been moved backwards as are the reverse plating needles during plain knitting;

Fig. 8 is a view similar to Fig. 7 and showing the relative positions of the needle protector and needles during rib knitting;

Fig. 9 is a view similar to Fig. 7 and showing the relative positions of the needle protector and a broken or defective needle which is in an elevated position and moved backwards into contact with the dial; and

Fig. 10 is a broken view showing in elevation

the cams and push rods for operating the needle protector.

In the drawings the invention is shown in connection with a circular rib knitting machine of a well known Scott & Williams construction, such as is shown in the patent to Scott, No. 1,641,101 of August 30, 1927, only such parts thereof being shown as are necessary to illustrate the application of the invention thereto. As shown in the drawing, there is the usual bed plate B, a needle cylinder 260 which is slotted to receive the needles N, a dial D having the two-part needles shown in the Scott patent referred to, and a dial cam D', the dial D being supported and driven by the shaft d. There is also provided the usual sinker or web holder ring 295 which supports the usual sinkers w¹ biased to their inner positions by the springband w⁶⁰ and operated by cams, not shown, in the usual cam cap 300.

The machine shown in the drawings is arranged to reversely plate fabric knit of two yarns by deflecting the cylinder needles during plain knitting and for this purpose the upper portion of the needle cylinder 260 is cut away forming a shoulder as at 260' which serves as an abutment for bending the needles backward in order to change the plating relation of the threads taken by the deflected needle. In order to deflect the needles for reverse plating any suitable means may be employed, the mechanism shown comprising pressers 20 mounted in the slots of selected cylinder needles and bearing against the needles at spaced points thereon, jacks 22 mounted in slots in a jack dial 23 secured to the under surface of the sinker ring 295 and normally biased to their inner positions so as to bear lightly against the pressers 20 by springbands 24. The jacks 22 are operated by suitable cams, not shown, to force the pressers 20 against the needles and bend backward the upper portion or hook end of the needle, the needles bending about the shoulder 260' as a fulcrum. The needles N are provided with the usual butts for operation by the usual cylinder needle operating cams, not shown.

To support a needle protector constructed in accordance with this invention a bolt or pin 30 is mounted in the base plate B and has journalled thereon a sleeve 32, the upper portion of which is enlarged as at 32^a to form a support for a cam plate 34 pivotally mounted on a cylindrical extension 32^b to the sleeve. The extension 32^b of the sleeve is divided vertically and the slot thus provided is enlarged at one point to receive a sleeve 36, the sleeve being secured in position by

the clamping action of the portions of the extension 32^b which are drawn together by the bolt 38. The sleeve is cut away at one end so as to provide a tapering downwardly bent end 36^a and serves to slidably support a needle detector 40 formed with a tapered end 40^a. At its other end the detector 40 is bent at right angles to provide a downwardly extending finger 40^b which engages in an eye 42 secured in an opening in the cylindrical extension 32^b by a set screw 43, the eye 42 limiting the outward movement of the needle detector 40 under the influence of a spring 44 which surrounds the needle detector 40 and is confined between the end of the sleeve 36 and a collar 46 on the detector 40.

Adjustably secured to the cam plate 34 by the set screws 48 is a cam 50 having a cam surface 50^a arranged to engage with the downwardly bent finger 40^b on the needle detector 40 as the cam plate 34 is rotated about the cylindrical extension 32^b of the sleeve. A spring 52 having one end connected to an extension of the cam plate 34 and its other end secured by pin 53 to the enlarged portion 32^a of the sleeve normally biases the cam plate 34 and cam 50 to a position in which the cam surface 50^a is disengaged from the finger 40^b of the needle detector 40, as shown in Figure 6.

To operate the cam plate 34 and cam 50 against the action of the spring 52 there is provided a link 54 connected at one end to the extension of the cam plate 34 and at its other end projecting through the upper end of a lever 39 pivotally mounted as at 61. A collar 55 secured on the link 54 ensures operation of the link 54 upon movement of the lever 39 in one direction. The lever 39 has the lower end thereof positioned to contact with cams on the main or other pattern drum 120. Operation of the lever 39 as the cams 40 on the drum 120 come beneath the lever causes the upper end of the lever 39 to be moved to engage with the collar 55 and shift the link 54 so as to rotate the cam plate 34 and cam 50 to the position shown in Figure 2 against the action of the spring 52 and move the detector 40 forward and upon release of the lever 39 by the cams on the drum 120 the collar 55 will be released by the lever 39 permitting the spring 52 to return the cam 50, cam plate 34 and link 54 to the position shown in Figure 6 and the detector 40 to be moved outwardly.

Secured to the lower end of the sleeve 32 by a set screw 57 is a crank arm 60 having an adjustable downwardly disposed extension 62 held in position by set screw 63 and mounted on the set screw 63 and held in position by nut 64 is an upwardly extending hook 65 to which is connected one end of a chain 66, the other end of which is connected to one end of a lever 68 which is pivotally mounted, as at 70, upon a stud 72 secured in a bracket 74 mounted on the base plate B. The other end of the lever 68 is engaged by the upper end of a push rod 460, the lower end of which is engaged by cams carried by the pattern drum 120. The push rod 460 is guided by the usual comb, not shown, and when raised by the cams on the drum 120 operates the lever 68 to rotate the sleeve 32 and needle detector 40 against the action of a spring 76, one end of which is secured to the extension 62 of the crank arm 60 while the other end is attached to the base plate B. The arrangement of push rod 460 and its connection to the sleeve 32 is such that when the push rod is raised by a cam the sleeve 75 32 is moved to a position such that the needle

detector 40 is in the solid line position shown in Figures 2 and 6 and when the push rod 460 is lowered as the cams pass from beneath the push rod the sleeve 32 is returned by the spring 76 to a position such that the needle detector occupies the dotted line position I, as shown in Figure 2.

Pivotedly mounted on the under face of the base plate B is the lever 80 having one end arranged to operate a link 82 connected to a suitable machine stopping mechanism, as in the patent to Elliott, No. 1,754,151 of April 8, 1930, while the other end of the lever 80 is positioned to be engaged by the extension 62 so that upon operation of the needle detector 40 by a broken or defective needle or loops which have loaded up on a needle to the dotted line position II, shown in Figure 2, the lever 80 is operated to release the stopping mechanism to stop the machine.

The cams on the drum 120 are so arranged that during the knitting of rib fabric and plain fabric by round and round knitting the push rod 460 is raised, operating the lever 68 to rotate the sleeve 32 so as to bring the needle protector from the inoperative position shown at I in Figure 2 to the operative position shown in solid lines in Figures 2 and 6. During reciprocating knitting of the heel and toe the push rod 460 is not raised and the needle protector is left in its inoperative position. During the knitting of rib fabric the cams operating the lever 39 do not engage the lever permitting the link 54, cam plate 32 and cam 50 to be held by the spring 52 in the position shown in Figure 6 and permitting the spring 44 to hold the needle detector 40 at the outermost position permitted by the adjustable eye 42, whereby the needle detector 40 is positioned as in Fig. 8 so as to be engaged by loops which "load up" on the needles.

During the knitting of plain fabric the push rod 460 is raised as during the knitting of the rib fabric and the lever 39 is operated by a cam on the drum 120 so as to cause the lever 39 to operate the link 54, the cam plate 34 and cam 50 against the action of the spring 52 and engage the cam face 50^a against the extension 40^b to force the needle detector 40 inwardly against the action of the spring 44 until the detector 40 assumes a position as in Figures 7 or 9. The needle detector 40 is thus provided with an inoperative position and two operative positions, an outer operative position assumed during rib knitting as shown in Fig. 8 in which the dial D is in a lowered position and the needle detector 40 is positioned to avoid the fabric but to be engaged by loops which load up on any needle and an inner operative position assumed during plain knitting as shown in Figs. 7 and 9 in which the dial D is in a raised position and the needle detector 40 is positioned to be engaged by a broken needle even when, as shown in Fig. 7, the needle moves backward into the recess provided for positioning the needles for reverse plating. In this inner position the needle detector 40 is positioned so as to be engaged by a needle which, because of a broken butt or other defect, is left raised to a position in which the point of the needle hook passes over the needle detector as in Fig. 9. The movement of the needle detector 40 from one to the other of its operative positions is effected without movement of the sleeve 36 so that the downwardly extending end 36^a of the sleeve 36 is positioned to be engaged by the sinks w' which assume an outward position on breakage or excessive stretching of the spring 75

band w^{60} in either operative position of the needle detector 40.

What is claimed is:—

1. A needle protector for knitting machines arranged to knit rib and plain fabric having a plurality of operative positions and machine operated means for shifting said protector from one operative position to another upon a change in the fabric knit.
2. A needle protector for knitting machines having a plurality of operative positions and machine operated means for shifting said protector from one operative position to another.
3. A needle protector for knitting machines having a plurality of operative positions automatically operating means for shifting said protector from one position to another and machine stopping mechanism operative upon engagement of said protector in either operative position.
4. A needle protector for rib knitting machines having one operative position during rib knitting and a different operative position during plain knitting and automatically operating means for shifting said protector from one position to the other.
5. A needle protector for knitting machines having an inoperative position and a plurality of operative positions and machine operated means for shifting said protector to the different positions.
6. A needle protector for knitting machines having an inoperative position and a plurality of operative positions, means for shifting said protector between an operative position and the inoperative position and separate operating means for shifting said protector between the operative positions.
7. A needle protector for knitting machines having an inoperative position and a plurality of operative positions, machine operated means for shifting said protector to the various positions and machine stopping means operative upon engagement of said protector in an operative position.
8. A needle protector for knitting machines arranged to knit rib and plain fabric having an outer operative position and an inner operative position and pattern controlled means for shifting said protector from one operative position to the other upon a change in the fabric knit.

9. A needle protector for a circular rib knitting machine having an operative position during rib knitting and machine operated means for shifting said protector from said operative position towards the needle cylinder to an operative position for plain knitting.

10. A needle protector for circular rib knitting machines having an outer operative position during rib knitting and an inner operative position during plain knitting and machine operated means for operating said protector from one position to the other.

11. A needle protector for circular rib knitting machines having a plurality of operative positions and means operative upon a change from rib to plain knitting for shifting said protector from one operative position to another.

12. A safety detector device for circular rib knitting machines, means operative upon a change from rib to plain knitting for shifting part of said device from one operative position with relation to the needles to another operative position therewith, and machine stopping mechanism operative upon engagement of said device in either operative position, said device having another part adapted to cause said machine stopping mechanism to be operated upon engagement of said part with a displaced sinker.

13. A needle protector for circular rib knitting machines having an inoperative position, one operative position during rib knitting and a second operative position during plain knitting, means operating said protector between its inoperative position and its position for rib knitting, separate operating means operating said protector between its operative positions and machine stopping mechanism operative upon engagement of said protector in either operative position.

14. A safety detector device for knitting machines, having a part adapted to occupy a plurality of operative positions with relation to the needles, machine operated means for shifting said part from one to the other of said operative positions, said detector also having a part adapted to be engaged by a displaced sinker, and machine stopping mechanism operative upon engagement of said last-mentioned part by a sinker.
